(57) **CLAIM**

The ornamental design for an extendable stand, as shown and described.

DESCRIPTION

FIG. 1 is a top, front and right side perspective view of an extendable stand, showing my new design;

FIG. 2 is a bottom, rear and left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 in FIG. 1;

FIG. 10 is an enlarged view of portion 10 in FIG. 1;

FIG. 11 is an enlarged view of portion 11 in FIG. 2;

FIG. 12 is an enlarged view of portion 12 in FIG. 5;

FIG. 13 is an enlarged view of portion 13 in FIG. 6; and,

FIG. 14 is an enlarged view of portion 14 in FIG. 8.

The evenly dashed broken lines illustrate portions of the extendable stand that form no part of the claimed design. The unevenly dashed broken lines define the boundaries of enlarged views and form no part of the claimed design.
